UNITED STATES PATENT OFFICE.

GEORGE F. SISBOWER, OF BAYSIDE, AND LOUIS E. PITTONI, OF NEW YORK, N. Y.,
ASSIGNORS TO NEW YORK COUCH BED COMPANY, OF LONG ISLAND CITY, NEW
YORK, A CORPORATION OF NEW YORK.

FOLDING COUCH.

1,414,051.

Specification of Letters Patent. Patented Apr. 25, 1922.

Application filed September 1, 1917. Serial No. 189,329.

To all whom it may concern:

Be it known that we, GEORGE F. SISBOWER, a citizen of the United States, residing at Bayside, in the county of Queens and State 5 of New York, and LOUIS E. PITTONI, a subject of the King of Italy, residing at New York city, in the county of Queens and State of New York, have invented certain 10 new and useful Improvements in Folding Couches, the following being a full, clear, and exact disclosure of the one form of our invention which we at present deem preferable.

For a detailed description of the present 15 form of our invention, reference may be had to the following specification and to the accompanying drawing forming a part thereof.

Our invention relates to a couch of the 20 telescoping type wherein one portion or section of the couch telescopes within the other portion or section. The invention involves means for enabling the movable or telescoping section to assume, when closed, a position inclined to the horizontal, so as to free 25 the mattress fabrics from interference with one another, but when in its open position it is lifted up at its rear edge to bring the fabrics into approximately the same level 30 and is also locked in that position.

In the accompanying drawing Figure 1 is 35 a perspective view illustrating a portion of a couch constructed in accordance with the invention. Figure 2 is an end view thereof.

Referring to the drawing A represents 40 one end of the stationary or principal frame and B the corresponding end of the movable or telescoping frame. Frame A is provided with the usual side bars C and D and frame B is provided with similar side bars E and F, the latter being, however, tubular and dropped down a certain distance below the 45 level of the top end rail, so as to bring it approximately on the level, but slightly higher than bar D of the frame A. The frame B is provided at its rear corners with rollers H that travel on inclined trackways G secured to the ends of frame A. On the inner end of each trackway is a normally 50 fixed block J onto which roller H rides as it approaches the outer end of its run, when the section B is drawn out. That serves to lift up the rear edge of frame B, so that its mattress fabric, which has

been on an incline due to the inclined course 55 of the trackways G, G, so long as it was under the fabric of frame A, will be brought up in a horizontal position and approximately on the same level as that of frame A. On the side bar F of frame B is a locking lug K which is rounded on its lower end and is located near the middle of the bed so as to take advantage of the natural 60 spring in the bar F and to some extent in the bar D. When the frame B is drawn forward the lug K is forced over and across the side bar D of the stationary frame by reason of the resiliency of the bar F, and drops down in front of said bar D. This 65 serves to lock frame B in its open position with the roller H upon the incline J, the bar F being properly spaced with relation 70 to the bar D so that this will occur. When the frame B is to be pushed back into its closed position, its outer edge may be lifted slightly to elevate bar F sufficiently to permit the lug K to clear the side bar D and free it therefrom, so that frame B can be 75 returned to its closed or telescoping position. This provides an extremely simple and yet 80 practical arrangement.

What we claim as new and desire to secure by Letters Patent is:

1. A telescoping couch comprising two 85 relative movable sections each provided with side bars, and end bars, the ends of one section being provided with fixed horizontally inclined disposed trackways the ends of the other section having portions contiguous to the side thereof in travelling engagement 90 with said trackways, and normally fixed blocks located at the inner ends of the trackways and lying within the plane of the contiguous side bar of said section, said blocks having portions for elevating the inner side 95 of the second section to bring both sections into approximately the same horizontal plane when the sections are in extended position.

2. A telescoping couch comprising two 100 sections one of which is provided with side bars lying in substantially the same horizontal plane, said section having trackways at its ends, the other section having a locking side bar provided with means positioned 105 to have locking engagement with the outer side of the contiguous side bar of the other section, said second section having end

frames provided with portions engaging said trackways and so positioned relative to the locking side bar as to cause the latter to move past the contiguous side bar of the first section before opening or separating movement of the sections is completed.

3. A telescoping couch comprising two sections one of which is provided with side bars lying in substantially the same horizontal plane, said section having trackways at its ends, the other section having a locking side bar provided with a depending rigid lug positioned to have locking engage-

ment with the outer side of the contiguous side bar of the other section, said second section having end bars provided with portions engaging said trackways and so positioned relative to the locking side bar as to cause the latter to move past the contiguous side bars of the first section before opening or separating movement of the sections is completed.

Signed this 29th day of August, 1917.

GEORGE F. SISBOWER.
LOUIS E. PITTONI.
